UNITED STATES PATENT OFFICE.

JOSEPH CLAPP, OF EVANSTON, ASSIGNOR TO THE CLAPP AUTOMATIC FIRE EXTINGUISHER COMPANY, OF CHICAGO, ILLINOIS.

AUTOMATIC VALVE.

SPECIFICATION forming part of Letters Patent No. 425,751, dated April 15, 1890.

Application filed July 29, 1889. Serial No. 319,021. (No model.)

To all whom it may concern:

Be it known that I, JOSEPH CLAPP, of Evans-
ton, in the county of Cook and State of Illi-
nois, have invented certain new and useful
5 Improvements in Automatic Valves, of which
the following is a full, clear, and exact de-
scription, reference being had to the accompa-
nying drawings, forming part of this speci-
fication, in which—

10 Figure 1 is a vertical sectional view of my
improved valve as it appears in its normal
position in connection with the supply, dis-
tributing, and air pipes of a fire-extinguish-
ing system. Fig. 2 is a sectional detail view
15 of a modified form of releasing mechanism.
Fig. 3 is an end view of said valve; and Fig. 4
is a side vertical sectional view of said valve,
in which the parts are represented in an ab-
normal position.

20 Like letters of reference in the different
figures indicate like parts.

The object of my invention is to provide an
automatic valve for normally closing the sup-
ply-pipe of a fire-extinguishing system, which
25 shall be simple in its construction and ef-
fective in its operation.

To these ends my invention consists in the
combination of elements more particularly
described and claimed.

30 Referring to the drawings, A represents
the shell of my improved valve, which is pro-
vided with induction and eduction openings
surrounded by pipes a a, which are screw-
threaded, respectively, for the reception of
35 induction and eduction pipes B C, the former
of which is represented as the supply and the
latter as the distributing pipe in a fire-ex-
tinguishing system. Upon the top of the
shell A is detachably secured a cap, prefer-
40 ably consisting of two parts a² a³, the former
of which is tapped into the shell, while the
latter is bolted thereto, as shown. A plug a⁴
is tapped into the part a³, into a bore in which
is inserted a projecting valve-stem d, to which
45 is attached a valve D in operative proximity
to a valve-seat a⁵. A small rod d', which
forms a continuation of the valve-stem, is
passed loosely through a cross-bar, as shown,
and serves to guide the valve in its movement.

50 Between the parts a² a³ of the cap is secured

a flexible diaphragm e, of rubber, leather, or
other suitable material, which is attached to
the valve-stem d between rings d² d³, rigidly
secured to said valve-stem, so as to cause
said diaphragm to move up and down there-
with and prevent leakage. This appliance
dispenses with the use of packing around the
valve-stem. Bolted or otherwise rigidly at-
tached to the cap are upright posts f f, ar-
ranged parallel to each other, to the top of
which is bolted a diaphragm-valve F, con-
sisting of a hollow metallic shell formed of
two parts f' f'', between which is secured a
flexible diaphragm f³, having a metal plate
f⁴ attached to the upper side, from which is
upwardly extended a stud f⁵. A cross-bar g
is arranged to bear upon said stud, one end
of said cross-bar being loosely attached to a
link g', which is in turn attached to a lug g²,
secured to the shell of the valve, while to the
other is suspended a bar g³, which passes
loosely through an opening in a rigid plate g⁴,
which prevents any but an up-and-down move-
ment of said bar. A weight h is attached to
the lower end of the bar g³, for the purpose
hereinafter stated.

In suitable proximity to said automatic
valve I provide an air-pump J, Fig. 1, which
is connected with the main distributing-pipe
c by means of a pipe j, in which is interposed
a check-valve j' to prevent a backflow of water
when the latter is admitted to the distribut-
ing-pipes. A branch pipe j² also connects the
pipe j with the chambers of the valve F. A
bifurcated bent lever K is inserted between
the standards f f and is provided with lugs
k k, which are pivoted at k' k' to said stand-
ards. Said lever is bent back substantially
at right angles to the parts k, as shown at k²,
and thence upwardly again in a single piece
k³, to the top of which is preferably attached
a weight k⁴. A link l is loosely attached to
said weight and is arranged to extend loosely
through a slot g⁵, formed in the bar g³. A de-
tent l' is adjusted to engage with a dog m, at-
tached to a cross-pin m', which is loosely piv-
oted to the standards f f. A cross-bar n is
loosely secured in bores formed in the legs of
the lever K and is provided with a set-screw
n', which is adapted to bear upon the upper

end of the valve-stem d when said bent lever is in its normal position.

I prefer to provide a secondary bent lever O , which is pivoted to the frame by means of a cross-bar o and is free to oscillate. One end of said lever is arranged beneath and normally in loose contact with a pin d^3 in the upper end of the valve-stem, while the other is bent upwardly, as shown at o , in near proximity to the lever K .

The operation of said valve is as follows: The valve D is first placed upon its seat, the lever K raised to the position shown in Fig. 1, the bar l inserted in the slot g^5 of the suspended bar g^3 , and the dog m placed in engagement with the detent l' , when the air-pump J is operated, thereby compressing air into the distributing-pipes and the diaphragm F , the pressure being sufficient to hold the weight h normally raised. The screw n' is then tightened sufficiently to prevent any leakage of the valve D . Upon the opening of an automatic sprinkler-head c in the distributing-pipes and the consequent escape of air the diaphragm in the valve F collapses, the weight h falls, the bar l is lowered, and the dog m turns upon its pivot, thus releasing the weighted lever K , which falls back in the position shown in Fig. 3. The set-screw n' is at the same time tilted upon its axis n , thus disconnecting it from the valve-stem d . Simultaneously the lever K strikes against the part o' of the lever O and unseats the valve D . This device insures the opening of the valve in the event that from any cause it should stick upon its seat so that the water-pressure would be insufficient to open it.

It is obvious that the mechanism for releasing the lever K may be modified from that shown in Fig. 1 without departing from the essential features of my invention. In Fig. 2 I have shown such modification, in which the pipe j^2 is connected at the side, the weight-sustaining bar being the valve-stem f^3 , which is carried downwardly directly through the valve-shell, taking the place of the bar g^3 , and a diaphragm p connected therewith to prevent leakage. In such construction the bar l may be pivoted to the standard f , the weight h may be placed upon one end thereof, and the dog m pivoted to the other.

Having thus described my invention, I claim—

1. The combination, with the supply and distributing pipes of an automatic fire-extinguishing system, of a valve arranged to act against the flow of water in the supply-pipe, a protruding valve-stem, a bent lever pivoted to the frame-work of the valve-shell, a set-screw in pivotal contact with the end of said valve-stem, a gravity-actuated tripping mechanism for releasing said bent lever, a diaphragm-valve in operative connection with said tripping mechanism, and means for introducing compressed air therein in common with said distributing-pipes, substantially as shown and described.

2. The combination, with the supply and distributing pipes of a fire-extinguishing system, of the valve D , inclosed within a suitable shell, stem d , bent lever K , set-screw n' , secured within a revoluble cross-bar, weight k^4 , toothed link l , dog m , weighted bar g^3 , diaphragm f^3 , in operative connection with the bar g , and a source of compressed air for normally raising said diaphragm and filling the distributing-pipes, substantially as shown and described.

3. The combination, with a valve and valve-stem, of a weighted oscillatory lever for normally holding the valve upon its seat and a supplemental lever pivoted to the frame and having one end connected with said valve-stem while the other is in operative proximity to said weighted lever, whereby the falling of the latter when released may force the valve from its seat, substantially as shown and described.

4. The combination, with the valve-stem d , of a bent oscillatory lever, tripping mechanism for holding the same in a normal position, and adjusting-screw n' , secured within a loose cross-bar pivoted within said lever, substantially as shown and described.

In testimony whereof I have signed this specification, in the presence of two subscribing witnesses, this 16th day of July, 1889.

JOSEPH CLAPP.
